WILLIAM H. BAZLEY, OF EVERETT, MASSACHUSETTS.

SAUSAGE-STUFFING MACHINE.

1,130,661.

Specification of Letters Patent. Patented Mar. 2, 1915.

Application filed May 12, 1911. Serial No. 626,716.

To all whom it may concern:

Be it known that I, WILLIAM H. BAZLEY, a citizen of the United States, residing at Everett, in the county of Middlesex, State 5 of Massachusetts, have invented a certain new and useful Improvement in Sausage-Stuffing Machines, of which the following is a specification, reference being had therein to the accompanying drawings.

10 Power-driven sausage-stuffing machines have been contrived employing a piston working within a cylinder, the latter having at its closed end one or more nozzles upon which casings or skins are placed, and 15 through which the filling material is forced into the said casings or skins by the movement of the piston toward the said closed end. The action of a machine of this type is interrupted from time to time by the 20 necessity for refilling the cylinder. For the latter purpose the piston has to be withdrawn from the cylinder to permit a fresh supply of filling material to be placed within the cylinder, after which the piston is 25 caused to reenter the cylinder. The refilling operations occupy some considerable time. Hence the working capacity of the machine is materially reduced.

The invention is combined with a power-driven sausage-stuffing machine employing a feed-screw or worm working within a cylinder, having a hopper or inlet in connection with the said cylinder through which a 30 continuous supply of the filling material 35 passes to the feed-screw or worm. The employment of a rotating feed-screw or worm, and a hopper delivering thereto, provides for continuous supply and feed of the material, and obviates all necessity for suspension of the working of the machine and the 40 performance of refilling operations on the order of those above set forth.

The invention provides for automatic control of the driving of the feed-screw or 45 worm, whereby the latter is rotated until the pressure within the cylinder reaches a predetermined amount, and then the speed of rotation of the feed-screw or worm is diminished, or the driving of the said screw 50 or worm is suspended, or the speed first is diminished and then on continued increase of internal pressure the driving of the feed-screw or worm is suspended. On the pressure being relieved the feed-screw or worm 55 is again caused to rotate, or is rotated at increased speed, and so on. Thereby a sub-

stantially uniform predetermined pressure is maintained within the cylinder. This enables filling operations to be carried on uninterruptedly, the feed-screw or worm and its automatically-controlled driving mechanism acting to keep up such pressure, and in the event of the latter reaching the predetermined degree or degrees during the time that the filling nozzles are closed and fresh 60 casings or skins are being applied thereto the automatic control either suspends the driving of the feed-screw or worm, or first diminishes the speed of the latter and then on further increase suspends the driving. 70 Thus the action of the feed-screw or worm is automatically taken care of, and all that is required on the part of the attendants upon the machine is to keep the hopper properly filled, and to apply casings or skins 75 to the filling nozzles from time to time.

The invention may be variously embodied. An embodiment of the same in the best form which I have thus far contrived is illustrated in the drawings, in which latter,— 80

Figure 1 shows a machine containing the said embodiment, partly in longitudinal section, partly in side elevation, and with a portion of the motor broken away. Fig. 2 shows the machine in plan, certain small 85 portions being broken away. Fig. 3 is a sectional view in the plane of the lines 3, 3, Figs. 1 and 2, showing the details of the thrust-bearing.

Having reference to the drawings, the machine is shown mounted upon a base-plate 1, which in practice may be of any suitable form and character. At 2 is the cylinder, it being fixed upon the said base-plate and provided with a funnel or hopper 3, the 95 opening of which communicates with the interior space of the cylinder. The said interior space is cylindrical and extends from one end to the other of the cylinder, the latter having openings at both ends. 100

At 4 is an end-cap which is secured to the cylinder at the delivery end of the latter, closing the opening of the cylinder at such end. The said end-cap is furnished with a nozzle-piece 5 with which are combined a 105 pair of nozzles 6, 6, each having a straight-way cock or valve 7 in connection therewith. The feed-screw or worm within the cylinder comprises a shaft 9 and a helical vane 10. The end-cap 4 is provided with convenient 110 means for securing it detachably in working position at the delivery end of the cylinder,

such means being of a character to enable the said end-cap to be quickly and conveniently unfastened and removed, or restored to place and again made fast. In the present instance the securing means comprises 5 swinging bolts 11, 11, each of which is mounted upon a pivot 12 between a pair of lugs 13, 13, upon the exterior of the cylinder at the delivery end of the latter, the end-cap 10 having open peripheral notches 14, 14, to receive the stems of the said swinging bolts and the threaded stems of the latter having nuts 15, 15, applied to the same.

Figs. 1 and 2 show the bolts 11, 11, in their 15 normal positions with their stems occupying the notches 14, 14, in the edge of the end-cap 4, and the nuts 15, 15, tightened up against the outer surface of the flange of the said end-cap, so that thereby the end-cap is locked and clamped securely in place.

It will be observed that the illustrated form 20 of securing means is especially contrived to withstand the internal pressure acting lengthwise of the cylinder, and transmitted from the vane of the feed-screw or worm, through the material which is advanced by the rotation of the said feed-screw or worm, toward and against the said end-cap. At the same 25 time, all that is necessary to be done in order to permit the end-cap to be removed is to slacken up the nuts 15, 15, and swing the bolts 11, 11, outward, which will unfasten the end-cap and permit it to be taken away.

I provide upon the feed-screw or worm, at 30 the head-end of the latter, and beyond the passageway or opening which leads from the funnel or hopper into the interior space of the cylinder, a disk or head 16 forming a part of or fixed upon the shaft 9 of the feed-

35 screw or worm, so that it rotates with the feed-screw or worm. This revolving disk or head is of a diameter to fit and snugly fill the interior space of the cylinder; it takes the place of a fixed end or head for the 40 cylinder. Except for the said revolving disk or head 16 the cylinder is entirely open at its head-end. The revolving disk or head closes the head-end of the cylinder, but in case any material should work past the edge 45 of the said disk or head such material will escape or discharge freely from the open head-end of the cylinder, and in consequence 50 jamming or clogging at the said head-end will be impossible.

55 The feed-screw or worm is in driving connection with an actuating or drive-shaft 17, which latter is arranged in line with the axis of the feed-screw or worm, and is mounted in suitable supporting bearings at 18, 19, 60 the said actuating or drive-shaft having combined therewith power driving-connections therefor as presently will be explained. The feed-screw or worm is detachably connected by a coupling of convenient form 65 and construction with the drive-shaft. In

the drawings, the shaft 9 is turned down beyond the disk or head 16 so as to form an annular shoulder 20 and an extension 21 of reduced diameter, this extension having a transverse slot 22 made therethrough, and the drive-shaft 17 is furnished with an axial socket 23 to receive the said reduced extension. Diametrically-opposite holes in the shell of the said socket receive a transversely-disposed wedge or tapering key 24, 75 which also passes through the slot 22 and bears by one edge against the outer end-wall of such slot. This wedge or key, through being driven tightly into place, acts to hold the end of the socket and the shoulder 20 of the shaft 9 of the feed-screw or worm in close contact, and locks the feed-screw or worm to the drive-shaft.

It will be observed that the central passage of the cylinder extends from end to end 80 of the cylinder and is of uniform diameter from end to end. Also that the unlocking and removal of the end-cap 4 gives access to the interior of the cylinder at the delivery end of the latter. It is further to be observed that upon driving out the wedge or key 24 the feed-screw or worm will be uncoupled from the drive-shaft 17, and may then be removed at the delivery-end of the cylinder by endwise movement through the 85 cylinder. Also, that when the feed-screw or worm has been thus removed the cylinder will be unobstructedly open from end to end of the same.

The described construction provides for 100 convenient and ready disassembling of the parts and for the cleaning thereof, as well as for the subsequent re-assembling and re-connecting of the parts in working relations and conditions again. The peripheral edge 105 of the disk or head 16 and the edge of the vane 10 of the feed-screw or worm are in bearing contact with the interior surface of the cylinder, and thereby the support of the feed-screw or worm within the cylinder, in 110 proper concentricity with the said interior surface, is provided for. The driving connections of the drive-shaft 17 comprise in the present instance a spur-gear wheel 25 which is fixed thereon, intermediate gearing 115 26 and 27, and a driving pinion 28 in connection with the shaft of an electric motor 29.

To permit the feed-screw or worm to yield by movement in the direction of its length in consequence of the reaction of the 120 material compressed toward and against the end 4 at the delivery end of the cylinder, in case the pressure within the cylinder should exceed the predetermined amount, I employ a yielding thrust-bearing in connection with the drive-shaft 17, and so combine the said drive-shaft with its bearings 125 as to be capable of a limited amount of endwise movement within such bearings, and also so mount the feed-screw or worm with 130

in the cylinder as to be capable of endwise movement inside the cylinder. The thrust-bearing for the drive-shaft 17 comprises in the present instance a block 30 between 5 which and the adjacent end of the drive-shaft a series of anti-friction balls 31, is interposed. The block 30 is mounted to slide upon a guideway on a fixed stand or shelf 32 and is backed up by expanding spiral 10 springs 33, 33, which are confined between the said block 30 and a second block 34 also mounted on the said stand or shelf 32 with capacity to move thereon. Block 34 is engaged by an adjusting screw 35 by means 15 of which the tension of the springs 33, 33, may be regulated. The said adjusting-screw 35 is fitted to a threaded hole tapped in an upwardly-extending lug of the stand or shelf 32.

20 The power-connections are controlled by means of a grooved collar 36 fixed upon the drive-shaft 17 and engaged by a fork upon one end of a lever 37 which is pivoted at 38, the said lever being connected by a link 39 with a switch-arm 40. The said switch-arm 40 is arranged to coact with contacts at 41, 41, in connection with an electric circuit. In the position of the parts and 25 switch-arm shown in Fig. 2 the feed-screw is being driven at the intended rate of speed, the circuit being closed and the motor in full operation. Endwise movement of the feed-screw and drive-shaft 17 toward the right will shift the switch-arm 40 to the 30 adjacent contact 41 and thereby either open the circuit and discontinue the action of the electric motor, or change the connection so as to cause the said motor to transmit rotary motion at a reduced rate of speed to 35 the drive-shaft and feed-screw or worm. In case the movement referred to of the switch-arm acts to reduce the speed of the drive-shaft and feed-screw or worm and it occurs that the pressure within the machine 40 continues to increase and still exceeds the predetermined limit, the further movement 45 of the switch-arm to the remaining contact 41 will open the circuit and cause the driving of the feed-screw or worm to cease. I 50 contemplate in the use of the machine keeping the cylinder fully charged with material so that there shall be a constant internal pressure maintained, which will involve the automatic reduction or suspension of the driving of the feed-screw or worm, and so 55 that when this pressure has been relieved by the filling of casings applied to nozzles 6, 6, the feed-screw or worm will be automatically speeded up or restarted and will 60 be rotated until the desired degree of compression shall again have been attained, and then allowed to decrease its speed or stand at rest.

The invention is not in all cases limited 65 to the employment of the precise driving

arrangements herein shown and described; nor is the employment of purely mechanical driving mechanism, mechanically controlled, precluded.

I claim as my invention:—

1. In combination, a cylinder having an outlet through which material contained within the cylinder is expressed, an expressing screw or worm within the cylinder acting by its spiral vane upon the said material, 70 power means for rotating the said screw or worm, and means for throwing the driving-power on and off controlled by the pressure within the cylinder and operating to maintain substantial uniformity of pressure 80 within the cylinder.

2. In combination, a cylinder having an outlet through which material contained within the cylinder is expressed, an expressing screw or worm within the cylinder acting by its spiral vane to express the material through the said outlet, power devices 85 for rotating the said expressing screw or worm, and power-controlling devices operated through the reaction of the material 90 upon the screw or worm to maintain substantial uniformity of pressure within the cylinder.

3. In combination, a cylinder, a screw or worm working within the said cylinder, 95 power devices for rotating the said screw or worm, and power controlling devices controlled by the pressure within the cylinder and operating to throw the power off and on to maintain substantial uniformity of 100 pressure.

4. In combination, a cylinder having an outlet through which material contained within the cylinder is expressed, a longitudinally-movable expressing screw or worm 105 within the cylinder acting by its spiral vane to express the material through the said outlet, power means for said expressing screw or worm and means whereby said power means is controlled as to its action in rotating the expressing screw or worm by the longitudinal position of the latter and acting to throw the power off and on to maintain substantial uniformity of pressure 110 within the cylinder.

5. In combination, a cylinder having an outlet through which material contained within the cylinder is expressed, a longitudinally-movable expressing screw or worm acting by its spiral vane to express the material through the said outlet, an electric motor in driving connection with the said screw or worm, and a controlling-switch for the said motor, itself controlled by the longitudinal position of the expressing screw or 120 worm and operating to throw the power off and on to maintain substantial uniformity of pressure within the cylinder.

6. A continuous-feed machine comprising an expressing screw or worm working 130

within a cylinder having an outlet through which material fed to the said screw or worm is expressed, driving means for the said expressing screw or worm, a shipper 5 for throwing the power on and off, and shipper-controlling means itself controlled by the pressure within the cylinder and operating to cause said screw or worm to rotate until a predetermined maximum 10 pressure is reached, then operate the shipper to discontinue the application of power,

and suspend the rotation until a reduction of pressure to the predetermined extent takes place, and then automatically apply the power to rotate the screw or worm. 15

In testimony whereof I affix my signature in presence of two witnesses.

WILLIAM H. BAZLEY.
